Inventor:

Henry E. Earle,

By T. C. Bracht.

Attorney.

UNITED STATES PATENT OFFICE.

HENRY E. EARLE, OF DANBURY, CONNECTICUT.

ADJUSTABLE ROD AND BOX FOR WATER, GAS, AND STEAM PIPES.

SPECIFICATION forming part of Letters Patent No. 307,753, dated November 11, 1884.

Application filed January 24, 1884. (No model.)

To all whom it may concern:

Be it known that I, HENRY E. EARLE, a citizen of the United States, residing at Danbury, in the county of Fairfield and State of Connecticut, have invented certain new and useful Improvements in Adjustable Rods and Boxes for Water, Gas, and Steam Pipes; and I do hereby declare the following to be a full, clear, and exact description of the invention, so such as will enable others skilled in the art to which it appertains to make and use the same.

My invention relates to improvements in adjustable rods and boxes for water, gas, and steam-pipes; and the object is to produce a device by which the cocks or valves in water, gas, and steam pipes can be easily and readily operated when said cocks or valves are placed at different depths or heights, and also that said device can be produced at a very reasonable expense, is not liable to get out of order or become inoperative, that it will not become easily filled up or clogged with loose earth, &c., and is always ready for use, and requiring no further adjustments or changes.

My invention consists, primarily, in an adjustable operating-rod with which the cocks or valves in water, gas, or steam pipes can be opened and closed when placed at different depths or heights, said rod being made in two sections sliding telescopically within each other. The lower section is provided with a key or wrench of any suitable size and shape to fit the plug of the valve or cock.

It also consists, in connection with said rod, of an adjustable box the sections of which can be telescopically adjusted with the rod.

It also consists in certain details of construction and arrangement of parts, as will be more fully described hereinafter, reference being had to the accompanying drawings and the letters of reference marked thereon.

Like letters indicate like parts in the accompanying drawings, in which Figure 1 is a vertical section of my device ready for operation with a pipe. Fig. 2 is a plan view of the upper part of the box. Fig. 3 is a detail view of the operating-rod. Fig. 4 is a cross-section on line xx . Fig. 5 is a detail of the lower end of the rod.

In said drawings, A represents the lower section of the operating-rod, which is provided at its lower end with a key or wrench, a , which

is made to suit any suitable size or shape of head of the cock or valve. This section is made tube-shaped, and terminates at its upper end in a square part, b , into which the upper section, B, of the rod fits, so that it can easily slide in it, so as to be adjusted to any desired depth or height. The section B is made of square shape, although it may be made hexagonal or other angular shape, to prevent it from turning. At its upper end this section is provided with a collar, c , secured thereto and placed at a proper distance from the top of said section to apply a key or wrench by which to operate the entire rod. This telescopic rod is placed into a box of proper size, also made in sections, so that the sections can be adjusted at the same time with the rod to accommodate itself with it. The lower section, C, is provided with a flange, d , to give it a firm bearing, and has at its upper end an inward-projecting flange, e . Into the section C is loosely fitted an upper section, D, also provided with an outer flange, f , arranged so that the two flanges, when coming in contact with each other, limit the movement of both and form a stop. The lower section is firmly secured into the ground, and has an enlargement, g , to receive the enlarged key or wrench.

To the upper section, D, which is screw-threaded at that end, is attached a box, E, having a cover, F, attached to it in any suitable manner. In the drawings the cover is shown provided with lugs h , which pass through notches i , Fig. 2, so that by giving said cover a quarter-turn it may be secured in place. Instead of this arrangement the cover may, however, be hinged and secured in any other suitable manner. The lower part of the box E is provided with lugs k , or ring which passes over the collar c on the rod B and holds it in place.

The key part of the rod A may be provided with a square or other shaped hole, as indicated by the dotted lines shown in Fig. 5.

The bottom of the box E, when placed onto the upper section, D, of the inclosing-box for the rod A B, serves to hold the adjustable box in position when placed in the ground, as represented in Fig. 1. The collar c also serves for the purpose of supporting the upper section, B, of the rod, and holding it in its proper position.

Having thus described my invention, what I claim, and desire to secure by Letters Patent, is—

1. An adjustable rod for operating the cocks or valves of water, gas, or steam pipes, made of an upper and lower section sliding telescopically into each other to suit different depths or heights, substantially as specified.
2. The combination of an adjustable rod for operating the cocks or valves of water, gas, or steam pipes, made of an upper and lower section, arranged to slide adjustably into each other, with a box consisting of an upper and lower telescopically-sliding section, as and for the purpose set forth.
3. The combination of an adjustable rod for operating cocks or valves of water, gas, or steam pipes, constructed as described, with an inclosing-box having an upper part provided with lugs or flange *k*, for holding the upper section, *B*, of the rod in place, as specified.
4. The combination of an adjustable operating-rod, *A B*, with an adjustable box consisting of the sections *C* and *D*, provided with the flanges *e* and *f*, respectively, as and for the purpose herein specified.
5. The adjustable operating-rod consisting of a solid section sliding telescopically in a tubular section provided with a key or wrench, as and for the purpose described.
6. The combination of an adjustable operating-rod, consisting of an upper and lower
- section sliding telescopically into each other, with an adjustable inclosing-box provided with a removable top section having lugs or flange *k* and a cover, *F*, arranged substantially as specified.
7. The combination of an adjustable operating-rod with an adjustable box consisting of the sections *C* and *D*, provided with flanges *e f*, and the lower section having the enlargement *g* and flange *d*, and the upper section provided with a street-box, *E*, with a cover, *F*, all arranged substantially as set forth.
8. The combination of an adjustable box made of telescopic sections, the upper section supporting the upper section of an adjustable operating-rod provided with a collar, and both rod and box arranged to be simultaneously adjusted, as and for the purpose specified.
9. The combination, substantially as described, of an adjustable operating-rod and an adjustable inclosing-box arranged to be operated simultaneously to suit different heights or depths, as and for the purpose set forth.

In testimony whereof I affix my signature in presence of two witnesses.

HENRY E. EARLE.
